UNITED STATES PATENT OFFICE

154,685

DESIGN FOR A WOMAN'S OVERSHOE

Areta L. Kelly, Chicago, Ill.

Application April 23, 1948, Serial No. 145,931

Term of patent 14 years

(Cl. D7—4)

To all whom it may concern:

Be it known that I, Areta L. Kelly, a citizen of the United States and resident of Chicago, in the county of Cook and States of Illinois, have invented a new, original, and ornamental Design for a Woman's Overshoe, of which the following is a specification, reference being had to the accompanying drawing, forming a part thereof.

Fig. 1 is a side elevational view of a woman's overshoe, showing my new design.

Fig. 2 is a perspective view of the same.

Fig. 3 is a rear elevational view of the same.

I claim:

The ornamental design for a woman's overshoe, substantially as shown.

ARETA L. KELLY.
